CLAIM

The ornamental design for an ant moat for hummingbird feeder, as shown and described.

DESCRIPTION

FIG. 1 is a top, front perspective view of ant moat for hummingbird feeder, showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is another perspective view of the ant moat for hummingbird feeder.

The broken lines in the drawings depict portions of the ant moat for hummingbird feeder, that form no part of the claimed design.

1 Claim, 8 Drawing Sheets
